SIGNAL OR ALARM SYSTEM

Joseph S. Jones, Brooklyn, N. Y., assignor, by
mesne assignments, to Chas. Cory Corporation,
New York, N. Y., a corporation of New York

Application June 14, 1936. Serial No. 115,955

1 Claim. (Cl. 177—314)

My invention relates to signal systems and apparatus, and in its broader aspect is not limited in utility. It is, however, in the present illustrative embodiment especially adapted for fire alarm systems and apparatus, and the description of the invention as adapted for this purpose, will sufficiently explain its utility and advantages.

An important object is to provide a signal or alarm system which may be actuated manually or automatically (either or both). As embodied in a fire alarm system, for example, there are one or more alarm circuits each provided with a visual and an audible signal (either or both) and including a plurality of automatic circuit closers, usually thermostats, which operate when the surrounding temperature rises above a predetermined normal limit, to operate the signals. Each alarm circuit also may include a manually operated circuit closer or "alarm box" and this may be arranged, as more fully explained hereafter, as a box having a glass seal and which will make the circuit operative when the seal is broken, and may also include means for operating the circuit by the use of a key or otherwise, without breaking the glass, this being used, for example, in manually testing the circuit.

Another important object is to provide the system with automatic supervising or testing means. Such means is devised in the present example to automatically operate a trouble signal which may be audible or visual, or both, whenever the alarm circuit is deranged by reason of an open circuit, failure of the normal supply current, or otherwise.

A further object is to arrange the main or alarm circuits as closed circuits, and the automatic supervisory circuits as open circuits, these circuits being so coordinated that if the alarm circuit becomes open for the reasons above mentioned or otherwise, the supervisory or trouble circuit is thereupon closed to call attention to the derangement of the alarm circuit.

The characteristics and advantages of the invention are further sufficiently explained in connection with the following detail description of the accompanying drawings, which show one representative embodiment of the invention. After considering this example, skilled persons will understand that many variations may be made, and I contemplate the employment of any structures that are within the scope of the appended claim.

In the drawings:

Fig. 1 is a diagram of a system embodying the invention in one form.

Fig. 2 is a front elevation of suitable annunciator boxes or central station apparatus.

Fig. 3 is a vertical section of the same, with parts broken away to save space.

Fig. 4 is a vertical section of one suitable alarm box, or combined alarm and test station.

Fig. 5 is a front elevation of the same.

The system is well adapted for installation in naval or other vessels where it is desirable to have a plurality of fire alarm circuits running to or through different parts of the ship, so that a fire alarm may be given automatically or manually at a central station. But the utility of the invention is not so limited, and it may be applied in any situation where similar protection is desired, for example, in factories or other buildings or industrial plants.

Figs. 2 and 3 show one suitable form or arrangement of annunciator boxes to be located at a central station. One of the boxes, as B, encloses a plurality of signal drops D which are desirably of the automatic reset type, one of these being provided for each alarm circuit. Mounted near or on the box is a bell signal A in circuit with all the drops and alarm circuits. Adjacent each drop is a lamp L, conveniently called a "trouble lamp", each of these lamps being in a supervisory circuit relating to the signal circuit in which the adjacent drop is located. Each pair of signals, that is, each drop D and its adjacent lamp L, is provided with a number to identify the corresponding circuit. In the other box B¹ are relays R, each corresponding to one of the alarm circuits and its pertinent supervisory circuit. Also, in this box are cutouts or circuit breaking switches C, one corresponding to each of the alarm circuits and identified by numbers in agreement with those on box B identifying the respective circuits.

There is also provided a buzzer-operating relay SE, (not shown except in the diagram, Fig. 1) which may be located at any convenient place.

Fig. 1 shows one suitable circuit arrangement including a plurality of alarm circuits, each including two conductors, as X and X¹, Y and Y¹, etc. Each of these alarm circuits runs to or through certain parts of the ship or other protected area and includes a plurality of the automatic signalling devices which are usually thermostats T shunted across the respective circuit lines as X, X¹. These automatic devices may be of any suitable type, such as electro-pneumatic, bi-metallic or mercurial, and in any case are arranged so that when the temperature rises above the predetermined normal maximum, the thermostat operates to short the circuit across the two circuit conductors, such as X, X¹. One of the conductors of each circuit, such as X, runs to the solenoid of the corresponding indicator drop D; in series with this drop is the corresponding cutout switch C, and the conductor then goes to the common terminal 1 of the signal bell A; from the other bell terminal a conductor 2 goes to negative line N. A branch

conductor from conductor X goes to one terminal of the solenoid 3 of a corresponding one of the relays R and from the other terminals of all the solenoids a common wire 4 goes to the 5 negative line.

The other alarm circuit conductor, as X¹, may go, as shown, directly to positive line P.

The armature 6 of each relay R, as graphically represented, constitutes a contact to co-operate 10 with a fixed contact 7. Contact 6 is in series with a corresponding one of the trouble lamps L, and from the other lamp terminal a conductor goes to a common lead 8 which runs to one terminal of battery 9. From the other battery 15 terminal a conductor 10 goes to the armature 11 of the buzzer relay SR which also constitutes, as graphically represented, a contact co-operating with a fixed contact 12 from which a conductor 13 goes to one terminal of the buzzer, and 20 from the other buzzer terminal a conductor 14 goes to a battery terminal to complete a circuit through the buzzer, battery, armature 11 and contact 10 when the relay SR is energized. Fixed contact 7 of relay R, above mentioned, is 25 connected to one terminal of the solenoid 15 of relay SR and the other solenoid terminal goes to the battery 9.

For each signal circuit, therefore, there is a 30 supervisory or trouble circuit including relay R, trouble lamp L, buzzer relay SR, buzzer S, and energizing battery 9, and suitable circuit conductors and arrangements above sufficiently explained.

To make the combined alarm and supervisory 35 circuits effective for the present purpose, a resistance K is shunted across the conductors as X, X¹ of each alarm circuit. One convenient arrangement or location of this resistance, e. g., in an alarm box, will be referred to hereafter in 40 describing one suitable type of box for giving an arbitrarily actuated fire alarm or for testing the system.

As so far described, the system operates as follows:

45 Resistance K is of such value that at all times a very small current, insufficient to operate the drop solenoid D, or the alarm bell A, flows through each alarm circuit traced from positive line P through conductor X¹, the resistance K, conductor X, the drop solenoid D, cutout switch C (normally in closed circuit position) alarm bell A, and negative line N. If, however, upon occurrence 50 of fire adjacent any of the thermostats T, the thermostat acts to short the alarm circuit across the conductors X, X¹, normal line current flows through the stated circuit and energizes the drop solenoid and throws the drop to visual position, and the current also passes through the alarm bell A, which sounds to peremptorily 55 attract the attention of the attendant to the visual signal, which indicates the approximate location of the fire or other condition causing the alarm. After taking proper steps to initiate fire fighting operations, the operator may move 60 the cutout switch C to open circuit position to break the alarm circuit, silence the bell A and cause the drop to move automatically to idle position. Otherwise, the cutout switch may be 65 operated for another purpose, presently explained.

70 Normally, line current flows through all of the solenoids 3 of relays R, thus retaining the corresponding armatures 6 in open circuit position, that is, the supervisory circuit is broken between contacts 6 and 7. If, however, at any time the

alarm circuit becomes "opened" by breakage of a conductor, failure of line current, or for other reasons, the relay solenoid is deenergized, permitting the armature to engage contact 7 and thus the supervisory circuit corresponding to the 80 particular alarm circuit is closed, the corresponding trouble lamp L is lighted, and the buzzer relay SR, common to all the supervisory circuits closes the buzzer circuit, sounding the 85 buzzer and forcibly attracting the attention of the attendant to the visual signal which indicates the defective circuit. He may thereupon operate the appropriate cutout switch C to open the signal circuit while repairs are effected. It will be noted that the supervisory or trouble 90 circuits are all energized from a source of power distinct and independent from the main supply line. This is important to insure that the trouble signals will be operated if the cause of trouble in the signal circuit is failure of the line 95 supply. A storage or primary battery is usually desirable for energizing the trouble circuits.

It is desirable in many cases to provide a signal box, illustrated in one form in Figs. 4 and 5, located at a convenient point in one or more of 100 the alarm circuits. This box or station AB is indicated diagrammatically in Fig. 1. When such a box or station is provided, the resistance K above referred to, is desirably located in the box, as shown in the diagram and in Figs. 4 105 and 5.

The box also desirably encloses spring contacts 20 and 21 in circuit with the respective alarm conductors X¹ and X. Contact 20 is provided with a button 22 resting against the inner face 110 of a glass 23 inserted in the front or door of the box. The box is also desirably provided with a hammer 24 connected by a chain 25 and available for breaking the glass, whereupon button 22 is free to move and the alarm circuit is closed 115 between contacts 20 and 21 to give a manual or arbitrary alarm of fire. This signal box is also available for testing purposes without breaking the glass, by the provision of a keyhole 30 designed for any suitable key, such as 31, Fig. 1, 120 which may be carried, for example, by a watchman or inspector, who may insert the key in the keyhole and by pressure upon the spring of contact 21 close the alarm circuit between contacts 125 21 and 20 for the purpose of arbitrarily testing the circuit.

I claim:—

An alarm annunciator system comprising a plurality of alarm circuits each of which includes 130 means for rendering them independently operative upon the occurrence of a predetermined condition, means for producing an audible alarm when said condition occurs, and an annunciator drop for each alarm circuit for visually indicating the exact location where the condition occurs, 135 manual means for independently opening each alarm circuit after the occurrence of the condition, a supervisory circuit including visual means for each alarm circuit for indicating when any of said circuits is open and a second audible 140 alarm operated simultaneously with said visual means, and a central control board on which are located both audible alarms, the alarm annunciator drops, the supervisory visual indicators and the manual means for opening the alarm circuits, said visual indicators being in 145 indicative relation with the annunciator drops so that the alarm circuit which is open may be identified.

JOSEPH S. JONES. 150
